(57) **CLAIM**

The ornamental design for the computer screen showing icon shape and arrangement, as shown and described.

DESCRIPTION

FIG. 1 is a front view of a computer screen showing icon shape and arrangement;

FIG. 2 is a front view thereof, shown rotated 180 degrees; and, FIG. 3 is a front view of the design of FIG. 1, shown rotated 90 degrees to the left.

The perimeters of the portion of the underlying computer screen and the icon shape and arrangement are understood to be flush.
